UNITED STATES PATENT OFFICE.

ARTHUR B. BELLows, OF PITTSBURG, PENNSYLVANIA.

CAR-SILL.

SPECIFICATION forming part of Letters Patent No. 762,796, dated June 14, 1904.

Application filed November 4, 1901. Serial No. 81,007. (No model.)

To all whom it may concern:

Be it known that I, ARTHUR B. BELLows, of Pittsburg, Allegheny county, Pennsylvania, have invented a new and useful Car-Sill, of which the following is a full, clear, and exact description, reference being had to the accompanying drawings, forming part of this specification, in which—

Figure 1 is a side elevation of a car-sill constructed in accordance with my invention. Fig. 2 is a cross-section showing the center and side sills of a car provided with my improved strengthening members. Fig. 3 is a detail side elevation, on a larger scale, showing the method of securing the strengthening members. Fig. 4 is a cross-section of the center sill of Fig. 3. Figs. 5 to 10, inclusive, are similar cross-sections showing modified forms; and Figs. 11 and 12 are detail views showing the preferred form of sill construction at the bolster.

My invention relates to the longitudinal sills employed in railway-cars, and is designed to provide a simple, cheap, and efficient construction which will take the place of the fish-belly form of sill now commonly employed and will enable commercial rolled shapes to be used and decrease the depth of the sill over the trucks.

Heretofore in order to obtain the necessary strength at the central portion of car-sills the webs of these sills have been commonly formed of gradually-increasing depth from the ends toward the center. The making of these sills, whether formed of pressed steel shapes or of a sheet with angles riveted along its edges, has been an expensive operation and necessitated the use of special and expensive machinery. My invention obviates this difficulty; and it consists in securing along the central part of the sill a separate longitudinal strengthening member, this member adding the necessary strength at the desired points.

The invention further consists in securing a strengthening member along the central part of the sill, this strengthening member having a vertical web, and, further, in using rolled shapes for both the sill and the strengthening member and in the special construction and arrangement of the parts, as hereinafter

more fully described, and set forth in the claims.

In the drawings, referring to Figs. 1 to 4, inclusive, in which I show a preferred form of my invention, 2 2 represent a pair of commercial rolled channels forming a center sill and having their flanges 3 turned outwardly. Along the central part of the length of each of these channels I rivet to the inner face of the web the longer leg 4 of a commercial angle, the flange 5 of which extends horizontally and is substantially parallel with the flange of the channel throughout the major portion of its length. At each end the strengthening-angle is preferably bent upwardly, as shown at 6, the flanges being cut away from the end portions to allow the web to lie in this form. The angle and channel may be secured together by rivets 7 or in any other desirable manner. If side sills are used, a single channel 8 may be employed, with a strengthening-angle 9 secured thereto in the same manner as in the case of the center sill, the side sill thus being similar to one-half of the center sill, as shown in Fig. 2. The turning up of the ends of the strengthening members may be used or not, as desired.

In the form of Fig. 5 I show a construction similar to that of Fig. 4, except that the flanges 5^a of the strengthening-angles are turned inwardly toward each other. In this form the ends of the strengthening members can of course be bent upwardly without the cutting away of the flanges.

In the form of Fig. 6 each strengthening member 5^b is composed of a plate 10, with an ordinary angle 11 secured along its lower edge with the flange turned outwardly. In the form of Fig. 7 the construction is the same as that of Fig. 6, plates 10' being used with angles 11', the flanges of the angles being turned inwardly, however, and extending toward each other.

In Fig. 8 I show the strengthening members as consisting of small channels having their upper flanges 12 secured directly to the lower flanges of the sill-channels.

In Fig. 9 I show the strengthening members as consisting of channels placed inside the sill-channels, with their webs riveted to-

gether, the flanges 12' of the strengthening-channels projecting inwardly toward each other.

In the form of Fig. 10 the strengthening members do not extend beneath the sill, but are in the form of simple angles riveted to the inner faces of the channels, with their flanges 11" extending inwardly toward each other on the same plane as the lower channel-flanges.

In all the forms shown the ends of the strengthening members may be and preferably are bent upwardly, except in the form of Fig. 8, where end web-plates may be used for securing the strengthening members to the sill.

In order to decrease the depth of the rolled section over the bolster, I preferably use, in connection with the additional strengthening member above described, a construction such, for example, as shown in Figs. 11 and 12—that is, I cut away the lower portions of the channels or other rolled shapes forming the center sill, as shown at 13, at points over the bolsters. I am thus enabled to use a deep channel or other shape, while at the same time the car-body is not raised unduly and a strong construction is afforded. In the form shown the lower flanges and part of the webs are cut away, strengthening-angles 14 are secured in pairs to the outer bases of the webs of the channels, and the center plate 15 is secured to an intermediate plate 16, fastened to the angles 14 and also to the angle-pieces 17 of the built-up bolster. This bolster, however, may be of any desired form, and its connection to the sill may be varied widely.

The advantages of my invention result from the simplicity and cheapness of construction of the sill. The sill and its strengthening member may be and preferably are formed of commercial rolled shapes, and where heretofore if a rolled shape were used for the sill the depth of sill over the trucks must be excessive. By the use of the added strengthening member along the central part I reduce the depth of the sill over the trucks, and thus decrease weight and also lower the car-body. By cutting away the center sill over the bolsters I increase the strength without elevating the car-body.

Many variations may be made in the construction and shape of the sill and its strengthening member or members without departing from my invention.

I claim—

1. A longitudinal car-sill consisting of a girder having a vertical web with flanges along its upper and lower edges, and a strengthening member of less length consisting of a rolled flanged shape, said strengthening member being secured at the intermediate parts of the sill member and below its top; substantially as described.

2. A longitudinal car-sill having a rolled-

shape member, said shape having a vertical web provided with a horizontal flange, and a strengthening member of less length than the sill consisting of a rolled flanged shape secured to its central portion, the strengthening member projecting below the sill member to which it is secured; substantially as described.

3. A longitudinal car-sill comprising a girder with a vertical web, and top and bottom angular flanges, and a strengthening member secured along the lower part of the girder and projecting below it, said strengthening member consisting of a rolled flanged shape of less depth than the girder.

4. A longitudinal car-sill having a flanged strengthening member of less length than the sill secured along its central portion and provided with bent-up ends extending above the lower plane of the sill; substantially as described.

5. A longitudinal car-sill containing a rolled shape having its lower portion cut away at the bolster-points, and strengthening members secured at the cut-away portions; substantially as described.

6. A longitudinal car-sill containing a rolled shape having its lower portion cut away at the bolster-points and provided with strengthening members at such portions, and bolsters secured to the web of the rolled shape at the cut-away points; substantially as described.

7. A longitudinal car-sill consisting of a girder having a vertical web with flanges along its upper and lower edges, said girder extending the entire length of the sill, and a strengthening member of less length, consisting of a rolled flanged shape, said strengthening member being secured to the sill member below its top; substantially as described.

8. A car-sill consisting of a shape having a vertical web and a horizontally-extending flange, and a strengthening member of less length than the sill member, and consisting of a flanged shape secured to its central portion, the strengthening member projecting below the sill member to which it is secured; substantially as described.

9. A longitudinal car-sill containing a flanged shape having its lower portion cut away at the bolster-points, and strengthening members secured at the cut-away portions; substantially as described.

10. A longitudinal car-sill consisting of a vertical web with angular flanges at the top and bottom, and a strengthening member of less length than the sill and consisting of a rolled flanged shape, said strengthening member being secured to the intermediate part of the sill and below its top; substantially as described.

11. A longitudinal car-sill consisting of a vertical web provided with angular flanges at the top and bottom, said sill extending throughout the length of the car-body, and a strengthening member secured to the sill below its top.

and terminating adjacent to the bolsters, said strengthening member consisting of a rolled flanged shape; substantially as described.

12. A longitudinal car-sill having a vertical web and angular flanges at its edges, and a strengthening member of less length secured to the intermediate part of the sill below its top, said strengthening member consisting of an angle; substantially as described.

13. A longitudinal car-sill consisting of a metal girder having a vertical web with flanges along its upper and lower edges, and a strengthening member of less length than the girder and secured to its intermediate part, said strengthening member consisting of a rolled flanged shape which is narrower than the girder; substantially as described.

14. A car-floor frame having a longitudinal sill consisting of two parallel metal girders each having a vertical web with flanges along its upper and lower edges, said girders arranged with their web portions vertical, and strengthening members of less length than the girders and secured to their intermediate parts below the top, said strengthening members consisting of rolled flanged shapes; substantially as described.

15. A car-floor frame having a center sill consisting of two parallel metal girders arranged with their web portions vertical and strengthening members of less length than

the girders and secured thereto with their ends terminating adjacent to the bolsters, said strengthening members being secured to the inner sides of the girders below their tops and each consisting of a rolled flanged shape; substantially as described.

16. A longitudinal car-sill consisting of a vertical web with top and bottom angular flanges extending parallel with each other throughout their entire length, and a strengthening member of less length than the sill and consisting of a rolled flanged shape, said strengthening member being secured to the intermediate part of the sill below its top; substantially as described.

17. A car having a longitudinal metallic car-sill extending beyond the bolsters and consisting of a vertical web with angular flanges at the top and bottom, and a strengthening member of less length than the sill and consisting of a rolled flanged shape, said strengthening member being narrower than the sill and secured thereto below the top of said sill; substantially as described.

In testimony whereof I have hereunto set my hand.

ARTHUR B. BELLows.
